UNITED STATES PATENT OFFICE.

CLINTON D. PALMER, OF CHICAGO, ILLINOIS, ASSIGNOR TO SEARS, ROEBUCK AND CO., OF CHICAGO, ILLINOIS, A CORPORATION OF NEW YORK

COMBINED STENCIL-PLATE AND RECORD-CARD.

1,136,972.

Specification of Letters Patent. Patented Apr. 27, 1915.

Application filed February 8, 1913. Serial No. 747,043.

To all whom it may concern:

Be it known that I, CLINTON D. PALMER, a citizen of the United States, residing at Chicago, in the county of Cook and State of Illinois, have invented certain new and useful Improvements in Combined Stencil-Plates and Record-Cards, of which the following is a specification.

In certain lines of business it is desired 10 at intervals to send printed matter to customers with whom certain business transactions have been had. Such mail matter is commonly addressed by means of addressing machines or other appliances employing stencil plates. These plates are filed in the same way that card indexes and card records are preserved. With the stencil plates heretofore commonly used, in order for the user to find desired stencil plates in the file, 15 20 and return them to their proper places, it has been necessary for him to read the name of the customer as represented by the cuts, perforations or the like constituting the letters of the stencil plate. These letters not being readily legible when the stencil plates are arranged in the file, the work of finding or identifying desired stencil plates has 25 30 been slow and laborious.

When the printed matter is to be sent 35 only to customers with whom certain business transactions have been had, as, for example, those who have bought a certain amount of goods, it is necessary to keep a record relative to dates and nature of transactions with each customer, and to consult this record before selecting stencil plates for the addressing operation.

One of the objects of my invention is to 40 combine the record of a customer's business transactions with the stencil plate for that customer, in order to obviate the necessity of consulting the record in one file, and thereafter selecting the stencil plate from another file.

Another object of the invention is to 45 provide a stencil plate having an identifying portion upon which the name of the customer may be legibly placed in order to facilitate the finding of desired stencil plates 50 from among the mass in the file.

It will be seen that the attainment of the foregoing objects renders it possible to have in one common file a perfectly legible index card carrying records for reference or

other purposes and also each card carrying its own stencil for addressing purposes.

A further object of the invention is to provide a combined record card and stencil plate of such construction that the stencil-plate portion may be utilized in placing the name and address upon the identifying portion.

Heretofore stencil plates for addressing machines have been provided with metallic or cardboard frames. Such stencil plates are thick and take considerable room for a relatively small number of plates. One of the objects of this invention is to dispense with the frames heretofore employed in connection with stencil plates, thereby largely reducing the cost of such devices, and greatly increasing the number of stencil plates which may be stored in a given space.

In the accompanying drawings, Figure 1 is a front elevation of a combined record card and stencil plate embodying the features of my invention. Fig. 2 is a rear elevation of said device. Fig. 3 is a view showing the manner in which the stencil plate portion may be used in stenciling the name and address upon the identifying portion.

In the drawings, 1 designates a card which may be of any suitable size and shape and of any suitable material, the preferred material being flexible and of such character as readily to receive written and printed matter, as for example, light cardboard. The card consists of a portion A which may, for convenience, be termed the identifying portion, a record-receiving portion B, and a stencil-plate portion C. The identifying portion A constitutes the upper end portion of the card, while the stencil-plate portion forms the lower end of the card.

The letters of the stencil-plate portion may be of any suitable character, as, for example, cut-out portions and perforations herein indicated.

That portion of the rear side of the card which is not utilized for the letters of the stencil plate may be ruled or otherwise prepared to receive written or printed records or memoranda.

It will be apparent from Fig. 1 that, in the front view of the combined record card and stencil plate, the letters of the stencil are inverted.

In the production of the device herein

shown, a card of the desired form and size, and having lines suitably ruled thereon, if desired, is placed in a stencil-cutting machine with the rear side of the card uppermost, or the card otherwise so disposed that the letters and characters composing the stencil shall be formed in the portion C as herein shown. The card is then laid upon a suitable support, as a, and flexed, as indicated in Fig. 3, to bring the stencil-plate portion C into position parallel to and in contact with the identifying portion A, a suitable inking device (not shown) being then applied to the portion C to form a 15 stencil impression upon the identifying portion A. After being flexed and the stencil impression made, the card assumes its original flat shape, thus forming a card with a stencil for addressing purposes at one end, 20 a perfectly legible impression of said stencil for filing and indexing purposes at the other end, and a portion of ample size for record purposes intermediate the two ends, the larger part of the rear side of the card 25 being also utilizable for records. When mail matter is to be sent out, the records on the cards are examined, and the desired cards selected from the file and placed in the addressing machine.

30 It will be seen that by my invention a stencil plate and a record card of ample size are associated so that when the record is found the stencil plate is at hand ready for immediate use; that the record-bearing 35 portion and the stencil-plate portion are provided with a perfectly legible identifying portion; that there can be no discrepancy between the stencil and the identifying portion, since the name and address are

printed directly from the stencil-plate portion; that the expense incident to the use of frames is obviated; and that a large number of the combined record cards and stencil plates may be stored in a comparatively small space. 40

I claim as my invention:

1. An integral combined record card and stencil plate comprising a paper sheet having an identifying portion at its upper end, a record-receiving portion intermediate its ends, and a stencil-plate portion at its lower end. 50

2. A combined record card and stencil plate formed wholly of flexible paper, one end of the card having openings therethrough forming stencil characters, the card being capable of being flexed to bring said end into contact with the opposite end of the card, the intermediate portion of the card being ruled to receive records. 55

3. A flexible card having in one end openings therethrough forming stencil characters, said end of the card being adapted to be placed in contact with the opposite end of the card to permit of applying ink therethrough said openings onto said opposite end, the space intermediate said ends on one side of the card being prepared to receive records, and the other side of the card exclusive of the portion bearing the stencil openings being also prepared to receive records. 60

In testimony whereof I affix my signature in presence of two witnesses.

CLINTON D. PALMER.
